UNITED STATES PATENT OFFICE.

JOHN N. JOERGER, OF KANSAS CITY, MISSOURI.

DESIGN FOR A CASING FOR A CYLINDER OILER.

Application filed October 16, 1922. Serial No. 3,995. Term of patent 14 years.

To all whom it may concern:

Be it known that I, JOHN N. JOERGER, a citizen of the United States, residing at Kansas City, in the county of Jackson and State of Missouri, have invented a new, original, and ornamental Design for a Casing for a Cylinder Oiler, of which the following is a specification, reference being had to the accompanying drawing, forming part thereof.

Fig. 1 is a perspective view of my new design for an ornamental casing for a cylinder oiler, and Fig. 2 is a plan view of the same.

I claim:

The ornamental design for a casing for a cylinder oiler, as shown.

JOHN N. JOERGER.
